C. HOLYLAND.

BADGE.

No. 16,197.

Patented Aug. 11, 1885.

UNITED STATES PATENT OFFICE.

CHARLES HOLYLAND, OF PITTSBURG, PENNSYLVANIA.

DESIGN FOR A BADGE.

SPECIFICATION forming part of Design No. 16,197, dated August 11, 1885.

Application filed May 2, 1885. Term of patent 7 years.

To all whom it may concern:

Be it known that I, CHARLES HOLYLAND, of Pittsburg, in the county of Allegheny and State of Pennsylvania, have invented a new 5 and useful Design for Badges, Medals, &c., of which the following is a specification.

My design, which is fully represented in the accompanying print, embraces as a central feature the monogram *a*, encircled by an annular surface or ring, *b*, which is in turn encircled by a garter, *c*.

The features above referred to are located on a field or background having four outwardly-extending points or corners, *d*, *e*, *f*, and *g*, 15 bearing, respectively, a stack of muskets, a pair of crossed sabres, an anchor, and a pair of crossed cannon, emblematic of the four branches of the military service. Between the corners are representations of rays of light, 20 *e*, radiated from the center.

Behind the features above described, but partially exposed, is a wreath composed on one side of laurel leaves *i* and on the other side of oak leaves *j*.

The features above described are commonly 25 arranged beneath the representation of an eagle, with flag, spears, cannon, and cannon-balls, as represented; but this portion is not an essential feature of the design.

What I claim is—

The design for a badge having as its essential features the circular field, the radiant points with arms thereon, and the wreath.

CHARLES HOLYLAND.
